US0D1097461S

(12) United States Design Patent (10) Patent No.: US D1,097,461 S
(45) Date of Patent: * Oct. 14, 2025

(54) SUIT

(71) Applicants: Jacob Tyer, Dunn, NC (US); Joy Young Allen, Dunn, NC (US)

(72) Inventors: Jacob Tyer, Dunn, NC (US); Joy Young Allen, Dunn, NC (US)

() Term: 15 Years

(21) Appl. No.: 29/896,561

(22) Filed: Jul. 5, 2023

(51) LOC (15) Cl. 02-02

(52) U.S. Cl.

USPC D2/743

(58) Field of Classification Search

USPC D2/728, 757, 714, 739, 743, 744, 779,
D2/841

CPC A41D 13/02; A41D 3/00
